FREDERICK APP, OF SELIN'S GROVE, PENNSYLVANIA, ASSIGNOR
TO HIMSELF AND J. S. BURKHART, OF THE SAME PLACE.

Letters Patent No. 87,389, dated March 2, 1869.

IMPROVED SCAFFOLD.

The Schedule referred to in these Letters Patent and making part of the same.

To all whom it may concern:

Be it known that I, FREDERICK APP, of Selin's Grove, in the county of Snyder, and State of Pennsylvania, have invented a new and useful Improvement in Scaffolds; and I do hereby declare that the following is a full, clear, and exact description thereof, which will enable others skilled in the art to make and use the same, reference being had to the accompanying drawings, forming part of this specification, in which—

Figure 1 is a side elevation of my improved scaffold.

Figure 2 is an end elevation of the same.

Similar letters of reference indicate like parts.

The object of this invention is to provide a scaffold for house-painters and other persons employed in working on the walls of buildings.

It consists, in general terms, of scaffolds, or platforms, arranged to raise and lower between two pairs of uprights forming the corner-posts of a frame, and provided with a winch or crank-windlass, and its accessory ropes and pulleys, arranged in such a manner, that a person or persons on the scaffold can raise or lower the same without leaving it.

In the drawings—

A are the corner-posts of the frame. These rise from the bed-frame B, and are surmounted by cross-timbers, C, to the upper sides of which are affixed the sheave-blocks D.

E is a movable scaffold, arranged between the posts A, in the manner shown.

The scaffold bears a winch, or hand-windlass, G, having bearings in a suitable frame, H, affixed to the scaffold, as shown.

There is a sheave, or grooved pulley, arranged in the frame H, and another one in a similar frame, I, at the opposite end of the platform.

There are three sheaves in one of the blocks D, and two in the other, and the rope working in the several sheaves is rove or arranged in the following manner:

One end of the rope is tied to some part of the platform, as the hook a. It then passes over one of the sheaves in the block D, then down and under the sheave in the frame I, thence up and over the second sheave in the first block D, and passes from that to the first sheave in the block D at the other end of the frame. It then descends to the winch-drum, and, passing through it, ascends again to the third sheave in the block. Thence passing down and under the sheave in the frame H, and up and over the middle sheave of the block, and from thence down to a second hook, b.

The red arrows indicate the direction in which the several parts move when the scaffold is being raised.

In order to hold the scaffold at different heights, I employ two cross-bars, J J, suspended below the scaffold by rods d, connecting the said cross-bars with the guide-bars e, affixed to the upper side of the scaffold, as shown.

The rods d are attached loosely to the guide-bars, so

as to allow the cross-bars to swing clear of the rest-plate K, when the platform is being raised.

Springs, M, attached to the cross-bars and scaffold, as shown, act to draw the former toward the posts after passing the rest-plates K, which latter have oblique edges, as shown, to bear off the cross-bars when the scaffold rises.

L are guard-plates, pivoted to the posts, in such relation to the rest-plates, that they will rest upon the said rest-plates in the manner shown, thus presenting curved or oblique edges, which operate to bear off the cross-bars of the scaffold, when the latter is descending from above the said guard-plates.

The object of this contrivance is to enable the scaffold to be lodged on the rest-plates, or lowered past them to any point below, without handling the said contrivances, for it will be seen that when the cross-bars are supported by the rest-plates, the guard-plates are lifted therefrom and rest on the cross-bars, but when the cross-bars rise clear of the guard-plates, the latter fall again in contact with the rest-plates and present oblique or curved edges, which guard or bear off the descending cross-bars, and thus prevent them from lodging on the rest-plates.

The lower corners of the guard-plates project slightly beyond the ends of the rest-plates, so that the cross-bars will encounter the guard-plates when the scaffold is ascending.

Pairs of rest and guard-plates are arranged at suitable intervals along the posts.

In order to lower the scaffold to any of the lower rest-plates, it is first raised, to clear it of the guard-plates then resting on the cross-bars, which plates will fall upon the rest-plates, as before described, and enable the cross-bars to pass down. The cross-bars must be lowered past the rest-plates, where they are designed to be lodged, and again raised, to bring the said bars under the guard-plates of the new position.

These contrivances enable the scaffold to be held at any point, in a stable and secure manner, by simply turning the winch, and are far superior to the ratchet-rack and catches heretofore employed in like situations.

O are diagonal braces of the frame.

P is a step-ladder for ascending to the platform.

By the arrangement of the rope and pulleys in the manner set forth, the scaffold is made to raise or lower parallel to itself, and afford the means for painters or others working on the walls of buildings, to work from the top of the wall downward, or from the bottom upward, as may be desired, without the usual delay in shifting the scaffold.

The springs M may be substituted by cords and weights, as will be obvious.

Having thus described my invention,

I claim as new, and desire to secure by Letters Patent—

1. The arrangement of the winch G, platforms H and

I, and the rope and pulleys, with reference to the frame and the platform E, whereby the centre of said platform is left unobstructed, both ends being raised and lowered simultaneously by the winch G, outside of one of the uprights, as herein shown and described.

2. The rest-plates K and guard-plates L, arranged on the frame-posts A, as described, in combination with

the movable cross-bars J of the scaffold, and spring M, (or its equivalent,) all as and for the purpose set forth.

FREDERICK APP.
